UNITED STATES PATENT OFFICE.

MARVIN C. LINDEMANN, OF HOLLAND, MICHIGAN, ASSIGNOR TO BAY VIEW FURNITURE COMPANY, OF HOLLAND, MICHIGAN, A CORPORATION OF MICHIGAN.

CABINET FOR RADIO RECEIVING SETS.

Application filed February 21, 1924. Serial No. 694,189.

This invention relates to cabinets for radio receiving sets and the object of the invention is to provide a cabinet of the character described including compartments for a radio receiving set, battery charger, batteries, tools and spare parts.

Another object of the invention is to provide a cabinet for radio receiving sets forming an attractive piece of furniture and in which the radio receiving set, battery charger, batteries and other parts are concealed when the cabinet is closed.

Another object of the invention is to provide a radio cabinet in which only the radio receiving set is exposed to view when the cabinet is opened.

A further object of the invention is to provide a cabinet for radio receiving sets adapted to accommodate the standard receiving sets of the base or panel type, a stationary or removable partition being provided between the receiving set and batteries and battery charger therefor notched to fit over the wires through which the receiving set is provided with current for operation.

A further object of the invention is to provide a cabinet for radio receiving sets including a stationary or removable partition dividing the cabinet into two main compartments, a compartment being provided at each end of the main compartments for accessory parts.

Another object of the invention is to provide a cabinet for radio receiving sets of substantially the form and appearance of a spinet and arranged on the interior to accommodate the different types of standard radio receiving sets.

These objects and the several novel features of the invention are hereinafter more fully described and claimed and the preferred form of construction by which these objects are attained is shown in the accompanying drawings in which—

Fig. 1 is a perspective view of the cabinet in the closed position.

Fig. 2 is a perspective view of the cabinet in the open position.

Fig. 3 is a front elevation of the cabinet in the open position to expose the radio receiving set to view.

Fig. 4 is an enlarged section taken on line 4—4 of Fig. 3.

As shown in Figs. 1 and 3 the cabinet

comprises a series of four legs 1 which are 55 secured to and support the cabinet proper. The cabinet is made so that in outward appearance it resembles the old fashioned spinet and the appearance of the cabinet may be easily varied by utilizing legs of the different period styles in modern furniture. The legs are secured to the bottom 2 of the cabinet and at each end the cabinet is provided with a compartment 3 in which a drawer 4 may be slidably mounted or the 60 cabinet may be provided with doors 5 to allow access to the compartments 3. The compartments 3 are utilized for the storage of surplus radio tubes or other accessory parts and tools. The central portion of 70 the cabinet is divided into two compartments 6 and 7 by the partition 8. As shown in Figs. 3 and 4 the compartment 7 is provided with a false bottom or box like addition 23 in order to provide the necessary 75 depth for the reception of radio batteries, battery chargers etc. and this portion 23 may be made of wood or metal and is secured to the base 2 of the cabinet in any suitable manner. The well known "A" and "B" 80 batteries for the radio receiving set and the battery chargers are positioned in the compartment 7 and the radio receiving set is positioned within the compartment 6. The wires connecting the batteries and the radio 85 receiving set extend through the apertures 24 and through the notches 9 cut in the lower edge of the partition which provide legs 10 which seat in the groove 11 in the bottom 2 of the cabinet. While this partition 8 may 90 be stationary it is preferably provided with openings 12 into which the fingers may be inserted for removing the partition and the partition is provided with a spring pressed ball 13 in the upper edge engaging a notch 95 14 in the stationary top portion 15 of the cabinet. By this construction the partition may be easily removed to allow removal or replacement of the batteries and may be as easily inserted in place again. The portion 100 16 of the top of the cabinet is hinged at 17 to the stationary top portion 15 of the cabinet. The front portion 18 of the cabinet is hinged to the portion 16 by the hinges 19 and the portion 18 is provided with knobs 20 105 whereby the portions 16 and 18 may be lifted and folded back onto the stationary top portion 15 as shown in Figs. 2 and 3. The por-

tions 16 and 18 enclose the radio receiving set which may be of the type shown in Figs. 3 and 4 mounted on a base board 21 or may be of the panel type indicated by dotted lines 5 22 shown in Fig. 4. A guard rail 25 is secured to the wall of the cabinet at each end of the compartment 6 as will be understood from Figs. 2, 3 and 4 so that the front portion 18 of the cabinet must be lifted above 10 the guard rails 25 before it may be turned on the hinge 19 and in closing the cabinet the portion 18 must be turned outwardly past the ends of the guard rails before the compartment may be closed. This construction 15 prevents the possibility of the portion 18 swinging inwardly when the compartment is being opened or closed and breaking the tubes or parts of the radio receiving set which would probably occur without the 20 provision of the guard rails 25.

As shown in Fig. 4 the top portion 26 over the compartment 7 is hinged to the stationary top portion 15 between the compartments by the hinge 27 and provides access 25 to the batteries and battery chargers without removal of the partition or panel 8 and for this reason the panel 8 may be stationarily secured in position if desired. In the closed position shown in Figs. 1 and 4 the 30 cabinet may be used as a table and has the outward appearance of the old fashioned spinet. By lifting the knobs 20 the portions 16 and 18 may be folded back on the top portion 15 as shown in Figs. 2 and 3 thus exposing the radio receiving set to view 35 and allowing the different adjustments to be made for the reception of radio signals. The compartment 6 is of sufficient size to receive most of the standard radio receiving 40 sets either of the panel type or of the type shown in Figs. 3 and 4, all of the battery connections as well as ground, aerial and loud speaker connections being made through the notches 9 and apertures 24 in the panel 8. 45 When the cabinet is closed it may be used as a table and also provides a flat top on which a loud speaker may be positioned when either in the open or closed position.

From the foregoing description it becomes 50 evident that the cabinet is excellently adapted for the accommodation of radio receiving sets and accessory parts, provides a piece of furniture which will add to the appearance of the room in which it is used and

provides a device which accomplishes the 55 objects described.

Having thus fully described my invention, its utility and mode of operation, what I claim and desire to secure by Letters Patent of the United States is—

1. A cabinet for radio receiving sets comprising a rectangular casing having a compartment at each end extending transversely of the casing, a series of legs supporting the casing, a removable panel extending longitudinally of the casing between the end compartments and dividing the central portion of the casing into a forward and a rear compartment, the casing being provided with a groove in the bottom in which the lower 70 edge of the panel is adapted to seat, the rear compartment in the center of the casing being closed by the removable panel and being adapted to contain a portion of a radio receiving set, the cabinet being provided with 75 hinged portions in the top over the forward and rear central compartments, the side of the cabinet for the forward compartment being hinged to the hinged top portion for the said compartment and folded over the 80 rear top portion of the cabinet, the forward compartment enclosed by the hinged top and side portions being adapted to contain the remainder of the radio receiving set and the panel being provided with notches in the 85 lower edge through which the wiring between the portions of the radio receiving set may extend, and a spring catch mounted in the upper edge of the panel and adapted to engage in the stationary portion of the top. 90

2. A cabinet for radio receiving sets comprising a casing having a compartment at each end extending transversely thereof, a stationary member of narrow width extending between the tops of the end compartments, a removable partition below the said member between the end compartments, the bottom of the casing being grooved to receive the partition, a spring catch member for positioning the upper edge of the casing 95 relative to the said stationary member, the lower edge of the partition having notches providing openings between the front and rear compartments.

In testimony whereof I sign this specification. 105

MARVIN C. LINDEMANN.
